UNITED STATES PATENT OFFICE.

HERMAN L. MADDOX, OF ASBURY PARK, NEW JERSEY.

VEHICLE-AXLE.

SPECIFICATION forming part of Letters Patent No. 639,178, dated December 12, 1899.

Application filed April 7, 1899. Serial No. 712,078. (No model.)

To all whom it may concern:

Be it known that I, HERMAN L. MADDOX, a citizen of the United States, residing at Asbury Park, in the county of Monmouth and State of New Jersey, have invented certain new and useful Improvements in Vehicle-Axes; and I do hereby declare the following to be a full, clear, and exact description of the invention, such as will enable others skilled in the art to which it appertains to make and use the same.

This invention relates to certain new and useful improvements in vehicle-axes.

The object of this invention is to construct an axle of which the journals or spindles are in duplicate, reversible, and interchangeable.

A further object of the invention is to construct an axle having reversible and interchangeable spindles or journals to provide against wear and tear of said spindles or journals and the total impairment of the vehicle on account of breakage of the exposed portion of the axle or spindle.

Another object of the invention is to construct a reversible spindle in which the portion of the same which is not in use will be entirely inclosed, thereby protecting the same from dust and dirt.

A still further object of the invention is to construct a reversible spindle which may be moved within its journal so that all parts of the same may be worn equally, as it is a well-known fact that the wear upon vehicle-spindles is always upon the underside of the same.

Briefly described, my invention consists of a tubular axletree having at each end an internal removable hollow fitting and having secured on its ends a collar which receives a specially-formed nut by which the reversible spindle is held in position, the latter consisting of two conical-shaped spindles connected together and separated by a central enlargement or integral collar, all of which construction will be hereinafter described and then particularly claimed.

In the accompanying drawings, Figure 1 is a longitudinal sectional view of a portion of the axletree, showing my improved reversible spindle in position. Fig. 2 is a perspective view of my improved reversible spindle. Fig. 3 is a cross-sectional view of the axletree and

spindle, taken on the line 3 3 of Fig. 1. Fig. 4 is a like view taken on the line 4 4 of Fig. 1. Fig. 5 is a perspective view of the internal removable fitting secured in the end of the 55 axletree.

Referring now to the drawings by reference-numerals, 1 indicates the tubular axletree, which at each of its ends is provided with exterior screw-threads 2, adapted to receive the 60 interior screw-threads on the sleeve portion 3 of the collar 4, which engages each end of the axletree. This collar 4 is also provided with exterior screw-threads and abuts against the end of the axletree, as shown in Fig. 1 of the 65 drawings. It is further provided with a central opening to receive one portion of the reversible spindle, as will be hereinafter specifically described. Engaging this collar 4 is a securing-nut 5, which while serving to hold 70 the reversible spindle in position also acts as a jam-nut for the hub of the vehicle.

My improved spindle consists of two equal parts 6, both slightly conical in form and each having the screw-threaded reduced outer 75 end 7 to receive the nut 8, which secures the wheel in position upon the spindle. By this construction a double or two independent spindles connected together are provided, and they are separated by a centrally-ar- 80 ranged collar 9, the one face of which when the spindle is in position in the axletree abuts against the outer face of the collar 4 and the other face of which is engaged by the securing and jam nut 5.

For the purpose of holding the spindle steadily in its position—that is, the one-half of same which is within the axletree—I provide an internal removable fitting or sleeve 10 within each end of the axletree. This fit- 90 ting or sleeve is provided with a central conical-shaped opening to receive the one part of the spindle and is preferably composed of wood or a soft metal, being held in position by a set-screw 11, engaging through the sleeve 95 portion of the collar 4 through the exteriorly-screw-threaded ends of the axletrees, with its end impinging upon the internal sleeve or fitting. I provide the same form of nut 8 for engaging the screw-threaded end of this por- 100 tion of the spindle which is within the axle- tree, and in case the outer nut should be-

come lost the internal fitting or sleeve may be removed and the nut engaging the inner end of the spindle employed for holding the wheel in position, as this nut is not essential for the holding of the spindle within the fitting and axletree.

I preferably place a washer 12 against the securing-nut 5 and also interpose a washer 14 upon the screw-threaded end of the spindle, though these are minor features of construction.

The screw-threads on the ends of the spindles and the interior screw-threads on the sleeve portion of the collar 4 are preferably made left-hand screws, so that in the forward movement of the vehicle the tendency would be rather to tighten than to loosen the connections. If, however, in any particular construction right-hand screws should be preferred or necessary, a key could be employed for preventing the unscrewing of the parts. The set-screw by which the internal fitting or sleeve is held in position also serves to hold the collars 4 rigidly in position upon the axletree.

To place the spindle in position, one end of each is placed within the tubular fitting or internal sleeve and the securing or jam nut then placed in position upon the collar 4, which firmly holds the spindle in position.

The interchangeable nut 8 will of course have to be placed on the end of the spindle which goes within the axletree after the spindle has been inserted in the internal fitting and before the internal fitting is secured within the axletree.

It will be observed that various changes may be made in the details of construction

without departing from the general spirit of my invention.

Having fully described my invention, what I claim as new, and desire to secure by Letters Patent, is—

1. In combination, with a hollow axletree a sleeve threaded on the ends of said axletree, a fitting arranged in the ends of the axletree, a set-screw engaging said sleeve and axletree with its inner end engaging the fitting, a reversible spindle having a centrally-arranged integral collar and reduced screw-threaded ends, and a securing-nut engaging said sleeve and collar to hold the reversible spindle in position, substantially as described.

2. In combination with a hollow axletree having exterior screw-threaded ends, a sleeve threaded on said ends and having an exterior screw-threaded collar 4, a hollow fitting arranged within the ends of the axletree, a set-screw passing through said sleeve and axle and impinging upon the hollow fitting to hold the latter in position, a reversible spindle composed of two tapering members formed integral and separated by a centrally-arranged collar 9, said members having reduced screw-threaded ends to receive securing-nuts, and a securing-nut 5, engaging the collar 4 and abutting against the collar 9 to hold the reversible spindle in position, substantially as described.

In testimony whereof I affix my signature in presence of two witnesses.

HERMAN L. MADDOX.
